UNITED STATES PATENT OFFICE.

HUGO RICHARD BAUER AND HERMAN FRANZ REINHOLD, OF CLIFTON, NEW JERSEY.

TAKE-UP STOP-MOTION.

1,342,272.

Specification of Letters Patent. Patented June 1, 1920.

Application filed December 2, 1919. Serial No. 341,921.

To all whom it may concern:

Be it known that we, HUGO RICHARD BAUER, a citizen of the United States, and HERMAN FRANZ REINHOLD, a citizen of the 5 United States, and both residents of Clifton, in the county of Passaic and State of New Jersey, have invented a new and Improved Take-Up Stop-Motion, of which the following is a full, clear, and exact description.

10 The invention relates to power looms provided with a stop motion, and its object is to provide a new and improved take-up stop motion arranged to prevent the formation 15 of a defective fabric by rendering the take-up inoperative and thereby preventing it from advancing the woven fabric in case the filling or weft threads breaks or runs out in the shuttle.

20 Another object is to prevent the weaver from restarting the loom unless the stop motion for the take-up is first reset.

Another object is to enable the weaver to quickly determine whether the loom was 25 stopped by the usual warp-controlled stop motion or by the usual filling-controlled stop motion, thus enabling the weaver to quickly make the necessary repairs.

Another object is to permit of attaching 30 the take-up stop motion to looms now in use and without requiring alteration in the construction of the loom.

Another object is to dispense with the use of a brake mechanism and thereby prevent 35 stripping of the gears in case of a sudden stop of the loom.

With these and other objects in view, the invention consists of certain novel features of construction as hereinafter shown and 40 described and then specifically pointed out in the claims.

A practical embodiment of the invention is represented in the accompanying drawings forming a part of this specification, in 45 which similar characters of reference indicate corresponding parts in all the views.

Figure 1 is a perspective view of the front end of a power loom provided with the improved take-up stop motion;

50 Fig. 2 is a side elevation of the same with the shipper lever in stopped position;

Fig. 3 is a sectional plan view of the same on the line 3—3 of Fig. 2;

55 Fig. 4 is an enlarged sectional side elevation of the forward end of the loom provided with the improved take-up stop mo-

tion, the parts being shown in position when the loom is running;

Fig. 5 is a cross section of the same on the line 5—5 of Fig. 4; and 60

Fig. 6 is a sectional side elevation of the same with the parts in position after the loom is stopped by the usual filling-controlled stop motion.

In power looms for weaving cloth or 65 other fabrics, and as now generally constructed, use is made of a warp-controlled stop motion and a weft or filling-controlled stop motion to stop the loom automatically in case the warp or the filling breaks, or the 70 filling runs out in the shuttle. During the time the filling stop motion begins to act until the loom comes to a dead stop, the take-up remains in action and the woven fabric is advanced with a consequent defect in the 75 fabric either through no filling in the pick and a consequent thin portion in the weave, or with two wefts in the same pick and a consequent increase in the thickness of the 80 weave, owing to the carelessness of the weaver in the proper adjustment of the take-up. In order to prevent this defect in the weave, use is made of a take-up stop motion, presently described in detail, and arranged to quickly render the take-up inop- 85 erative and thus prevent an undesired advance of the fabric until the loom is again in proper working order and the take-up stop motion is reset.

The power loom on which the take-up 90 stop motion is shown applied is provided with a suitable take-up mechanism, such, for instance, as the well known Knowles ratchet ring take-up, shown in Fig. 1, and which consists essentially of a ratchet 95 wheel 10 rotated intermittently by the dog 11 held on the forward end of a pitman 12 actuated from the usual crank shaft of the loom. The ratchet wheel 10 is engaged by a pawl or a catch 15 to prevent return 100 movement of the ratchet wheel 10 and consequent unwinding of the cloth woven and passing around the guide cloth roll 16 and the sand roll 17, to wind up on the bottom roll 18 in the usual manner, and 105 which rolls 17 and 18 are driven from the take-up ratchet wheel 10 by the usual gearing 20, as indicated in Fig. 1. The power loom is further provided with a stop motion controlled by the filling, and such, for 110 instance, as that known as the Knowles center stop motion adapted to actuate the

shipper shaft 25 provided at each end with a shipper handle 26 and journaled in the main frame 29 and in a bracket 27 attached to the under side of the usual breast beam 28 attached to the loom frame 29 at the front end of the machine above the take-up mechanism. The filling controlled stop motion is provided with a tumbler finger 30 fastened to the shipper shaft 25 5 and actuated by a pin 31 projecting from the tumbler 32 adapted to be actuated by the dagger 33 controlled by the feeler wires whenever the filling breaks or runs out to stop the loom.

10 The take-up stop motion is presently described in detail and is controlled by the pin 31 of the tumbler 32 and connects with the pawl or catch 15 to lift the latter out of engagement with the ratchet wheel 10 immediately after the tumbler pin 31 begins 15 to actuate the tumbler finger 30. For the purpose mentioned use is made of a shaft 40 journaled in suitable bearings 41 and 42, of which the bearings 41 are secured to the main frame 29 while the bearing 42 is attached to the breast beam 28 approximately at the middle thereof. On this shaft 40 is secured a tumbler finger 43 extending with its free end under the tumbler pin 31 at the 20 time the loom is running, and the other tumbler finger 30 of the filling stop motion is likewise in engagement with the said tumbler pin 31, as plainly shown in Fig. 4. On each end of the shaft 40 is secured a lifting arm 45 in which is adjustably held an eye bolt 46 by the use of nuts 47 and 48, and this eye bolt 46 is connected by a chain or other flexible connection 49 with the pawl or catch 15 to lift the latter out of engagement 25 with the ratchet wheel 10 whenever the take-up stop motion is actuated, as hereinafter more fully explained. On the shaft 40 is secured an upwardly extending arm 50 provided with a slot 51 through which extends a pin 52 projecting from one side of a shipper retaining member 53 pivoted at 30 on an arm 55 and adjustably secured by a set screw 56 on a bracket 57 adjustably secured by a bolt 58 to the top of the loom frame 29 adjacent the corresponding end of the breast beam 28. The bolt 58 extends through a slot 59 formed in the corresponding bracket 57 to allow of adjusting the latter forward or backward to correctly position the arm 55, which latter is held transversely adjustable on the bracket 57 to correctly locate the shipper retaining member 53 and its pin 52 relative to the slotted arm 50. The pivoted member 53 is provided at 35 its inner side with a pin 60 engaged at its under side by the V-shaped top of a rod 61 mounted to slide at its lower end in a bearing 62 forming part of the arm 55 of the bracket 57. A spring 63 is coiled on the rod 61 and is seated at its lower end on the

bearing 62 and presses at its upper end on a shoulder 64 formed on the rod 61 thus exerting an upward push on the rod 61 with a view to move the pivoted member 53 quickly into an uppermost horizontal position, as hereinafter more fully explained. The member 53 has a rule joint connection with the arm 55 to limit the swinging movement of the pivoted member 53. 70

When the pivoted member 53 is in uppermost and approximately horizontal position, as shown in Figs. 2, 3 and 4, then its free end extends into the path of the shipper handle 26 at the time the latter is in stopped position (see Figs. 2 and 6) to prevent the weaver from moving the shipper handle 26 from the stopped position into starting position. In order to enable the weaver to start the loom it is necessary for him to swing the pivoted member 53 downward into an approximately vertical position, shown in Figs. 1, 4 and 5, to allow the weaver to move the shipper handle 26 from the stop position into starting position to re-start the loom. When the member 53 is swung into an approximately vertical position it is held therein by the spring-pressed rod 61 (see dotted lines in Fig. 2) and when a rocking motion is given to the shaft 40 by the tumbler finger 43 then the arm 50 imparts a swinging motion to the member 53 in a rearward direction, and as soon as the spring-pressed rod 61 has passed the vertical position then it is forced upward by its spring 63 and thus quickly swings the member 53 into uppermost position thereby imparting a quick swinging movement to the arm 50 to quickly rock the shaft 40 and thereby cause the lifting arm 45 to exert an upward pull on the flexible connection 49 to swing the pawl or catch 15 upward out of engagement with the ratchet wheel 10. Thus the ratchet pawl 15 is lifted out of engagement with the ratchet wheel 10 prior to the loom coming to a stop in case the filling breaks or runs out. The shipper shaft 25 is actuated by its tumbler finger 30, in the usual manner. It will be noticed that as soon as the pawl 15 is swung out of engagement with the ratchet wheel 10, the take-up mechanism becomes inoperative and consequently the woven cloth is not advanced to prevent a defect in the cloth by the missing of a filling or by subsequently placing two fillings in the same pick. 90

95

100

105

110

115

120

125

130

It is understood that when the loom is running, the shipper handle 26 is approximately in a vertical position, as shown in Figs. 4 and 5, and the two tumbler fingers 30 and 43 are both in engagement with the tumbler pin 31, and the pawl 15 is in engagement with the ratchet wheel 10. Now in case the filling breaks and runs out of the shuttle, the dagger 33 is actuated by the feeler wires and a downward swinging movement is given to the tumbler 32 whereby both

tumbler fingers 30 and 43 are swung downward to rock the shafts 25 and 40. The rocking of the shaft 25 causes a stopping of the loom and the rocking of the tumbler finger 43 causes a quick lifting of the pawl 15 out of engagement with the ratchet wheel 10 so that the take-up mechanism is rendered inoperative prior to the stopping of the loom.

It will be noticed that when the shaft 40

10 is actuated, as above explained, the retaining member 53 for each shipper handle 26 is moved into an approximately horizontal position thus holding the tumbler finger 43 in lowermost inactive position, as shown in

15 Fig. 6, at the same time preventing return movement of the shipper handle 26. Now in order to re-start the loom by pulling the shipper handle 26 into vertical position it is necessary for the weaver to swing the re-

20 taining member 53 downward into an approximately vertical position to rock the shaft 40 in a reverse direction and thus allow the pawl 15 to swing back into engagement with the ratchet wheel 10 and to move the

25 tumbler finger 43 back into engagement with the tumbler pin 31. It will also be noticed that by the use of the retaining member 53 the weaver can quickly see whether the loom was stopped by the usual

30 warp stop motion or by the filling stop motion, that is, as long as the retaining member 53 is in vertical position it is not affected on the warp stop motion being actuated but only when the filling stop motion

35 is actuated, as above explained. It will further be noticed that the take-up stop motion can be readily attached to a loom now in use and without alteration in the construction thereof.

40 A brake mechanism for quickly stopping the loom is not necessary as the take-up is rendered practically inoperative prior to the loom coming to a stop and hence the cloth is not advanced.

45 Having thus described our invention, we claim as new and desire to secure by Letters Patent:—

1. In a loom, a filling controlled loom stop motion adapted to stop the loom, a take-up and a take-up stop motion controlled by a member of the said filling controlled stop motion to render the take-up inoperative prior to the stopping of the loom, and means controlled by the said take-up stop motion and adapted to prevent restarting of the loom until the take-up stop motion is reset.

2. In a loom, a stopping and starting device for the loom including a shipper handle, a loom stop motion controlled by the filling and connected with the said stopping and starting device to stop the loom on the breaking or running out of the filling, a take-up and a take-up stop motion connected with the said take-up and con-

trolled by the said filling controlled stop motion to render the said take-up inoperative prior to the stopping of the loom by the said stopping and starting device, and means controlled by the said take-up stop motion and adapted to extend into the path of the said shipper handle to prevent restarting of the loom until the take-up stop motion is reset.

3. In a loom, a filling controlled loom stop motion having a tumbler, a take-up having an intermittently driven ratchet wheel, and having a pawl engaging the ratchet wheel, a take-up stop motion for the said take-up and comprising a shaft, a tumbler finger adapted to be actuated from the said tumbler, a lifting arm on the said shaft, an adjustable eyebolt in the lifting arm, and a flexible connection connecting the said shaft arm with the said pawl to lift the latter out of engagement with the ratchet wheel on rocking the shaft by the action of the said tumbler and tumbler finger.

4. In a loom, a filling controlled loom stop motion having a tumbler, a take-up having an intermittently driven ratchet wheel and having a pawl engaging the ratchet wheel, a take-up stop motion for the said take-up and comprising a shaft, a tumbler finger adapted to be actuated from the said tumbler, a connection between the said shaft and the said pawl to lift the latter out of engagement with the ratchet wheel on the said shaft being actuated by the said tumbler and tumbler finger, and means controlled by the said shaft and adapted to prevent restarting of the loom until the said take-up stop motion is reset.

5. In a loom, a filling controlled loom stop motion having a tumbler, a take-up having an intermittently driven ratchet wheel and having a pawl engaging the ratchet wheel, and a take-up stop motion for the said take-up and comprising a shaft, a tumbler finger adapted to be actuated from the said tumbler, a lifting arm on the said shaft, a flexible connection connecting the said shaft arm with the said pawl to lift the latter out of engagement with the ratchet wheel on rocking the shaft by the action of the said tumbler and tumbler finger, a slotted arm on the said shaft, and a spring-pressed pivoted member engaged by the said slotted arm to swing the latter from normal set position into the path of the shipper handle of the loom to prevent restarting of the loom until the take-up stop motion is reset.

6. In a loom, a filling controlled loom stop motion having a tumbler, a take-up having an intermittently driven ratchet wheel and having a pawl engaging the ratchet wheel, and a take-up stop motion for the said take-up and comprising a shaft,

a tumbler finger adapted to be actuated from the said tumbler, a lifting arm on the said shaft, a flexible connection connecting the said shaft arm with the said pawl to lift 5 the latter out of engagement with the ratchet wheel on rocking the shaft by the action of the said tumbler and tumbler finger, a slotted arm secured on the said shaft, a bracket fixed to the loom frame, a pivoted 10 member fulcrumed on the said bracket and provided with a pin engaging the slot in the said slotted arm, and a spring-pressed rod mounted to slide at one end in the said bracket and pivotally connected with the 15 said pivoted member to normally hold the said pivoted member in an inactive position and to move the said pivoted member quickly into active position relative to the shipper handle of the loom after the said 20 pivoted member is started from its inactive position by the said slotted arm.

7. In a loom, a take-up stop motion, comprising a shaft, a tumbler finger secured on the said shaft and adapted to be actuated by 25 the tumbler of a filling stop motion, a lifting arm on the said shaft and provided with a flexible lifting member adapted to be connected with the pawl of a take-up ratchet wheel, a slotted arm secured on the said 30 shaft, a bracket adapted to be attached to the loom, a shipper retaining member pivoted on the said bracket and provided with a pin engaging the slot in the said slotted arm, and a spring-pressed rod slidable at 35 one end on the said bracket and pivotally connected with the said shipper retaining member to normally hold the latter in in-

active position and to move the said shipper retaining member into active position relative to the shipper lever of the loom 40 after the said shipper lever member is started by the said slotted arm.

8. In a loom, a stopping and starting device for the loom including a shipper handle, a loom stop motion controlled by the filling, a take-up, a stop motion for the take-up controlled by the filling stop motion, a retaining member, movable in and out of the path of the shipper handle, and means controlled by the take-up stop motion for holding said retaining member in the path of the shipper handle.

9. In a loom, a stopping and starting device including a shipper handle, a loom stop motion controlled by the filling, a take-up, 55 a stop motion for the take-up controlled by the filling stop motion, a pivoted and spring actuated retaining member movable in and out of the path of the shipper handle, and controlled by the take-up stop motion for holding the said retaining member in the path of the shipper handle.

10. In a loom, a stopping and starting device including a shipper handle, a loom stop motion controlled by the filling, a take up, a 65 stop motion for the take up controlled by the filling stop motion, a pivoted retaining member adapted to extend into the path of the shipper handle and controlled by the take up stop motion, and a spring actuated 70 rod engaging the said retaining member.

HUGO RICHARD BAUER.
HERMAN FRANZ REINHOLD.
